MOSES MOSLER, OF CINCINNATI, AND CARL BARTELS, OF HAMILTON, OHIO, ASSIGNORS
TO THE MOSLER SAFE COMPANY, OF NEW YORK, N. Y.

SAFE CONSTRUCTION.

1,113,236.

Specification of Letters Patent.

Patented Oct. 13, 1914.

Application filed November 23, 1913. Serial No. 803,484.

To all whom it may concern:

Be it known that we, MOSES MOSLER, a citizen of the United States, residing at Cincinnati, Hamilton county, Ohio, and CARL BARTELS, a citizen of the United States, residing at Hamilton, Butler county, Ohio, have invented certain new and useful Improvements in Safe Construction, of which the following is a specification.

This invention, pertaining to safe or vault construction, has been devised primarily with a view to the construction of safes of unmachinable metal, such as manganese steel castings, the aim being to produce a safe-wall formed of several thicknesses of metal without the necessity for one layer depending upon a contiguous layer for its stability.

The invention will be readily understood from the following description taken in connection with the accompanying drawings in which:

Figure 1 is an exterior view of one of the walls of a safe embodying our invention: Fig. 2 a perspective section of one lower corner of the safe in the planes of lines *a* and *b* of Fig. 1: Fig. 3 a horizontal section of a portion of the wall, that portion of the section above line *c* being in the plane of line *d* of Fig. 4, while that portion of the section below line *c* is in the plane of line *e* of Fig. 4: Fig. 4 a vertical section through the wall, that portion of the section above line *f* being in the plane of line *g* of Fig. 3 while that portion of the section below line *f* is in the plane of line *h* of Fig. 3: and Fig. 5 a horizontal section illustrating a somewhat modified construction.

In the drawings:—1. indicates the general safe structure: 2, one of the side plates thereof: 3, another of the side plates, at right angles to plate 2: 4, a vertical corner plate with its edges adjoining the edges of plates 2 and 3: 5, a horizontal plate at one lower corner of the safe: 6, an upwardly projecting portion of plate 5 to cause that plate to become a lower corner plate, the upper edge of portion 6 adjoining the base of plate

3: 7, a corner plate at the juncture of two vertical plates and the lowermost horizontal plate, the upper edge of this corner plate adjoining plate 4 while one of its vertical edges adjoins portion 6 of plate 5: 8, studs projecting inwardly from the plates which have been referred to in lines at each side of the joints between the edges of the plates: 9, bars secured against the inner surface of the plates at each side of the joints between the edges of the plates, one of these bars overlapping the joint between the plates and being, preferably, beveled where it abuts against the contiguous bar, these bars 9 being secured to the plates by means of perforations through the bars engaged by studs 8, the inner ends of the studs being riveted at the inner faces of the bars, and the bars being of machinable metal: 10, a coverstrip overlying the abutting joints between the bars 9: and 11, screws passing through the coverstrips and threaded into the bars 9.

Assuming the wall-plates thus far referred to as being formed of unmachinable metal, manganese steel castings, for instance, all of the joints between the edges of plates may be formed on the coverstrip method set forth, and when the wall-plates have been thus joined there is formed a complete safe-wall providing such security as is incident to the thickness of the plate.

It should be here stated that in order to fit plates of manganese steel castings for purposes of safe-construction, the castings require to be heat-treated, and in order that the heat-treatment may be effective throughout the thickness of the plates they must be made of limited thickness.

The particular method of joining the edges of the plates which has been herein set forth in exemplifying our present invention, is not new, being set forth in United States Patent No. 1063317, granted June 3rd, 1913, to The Mosler Safe Company assignee of Bartels, one of the present inventors. The particular devices set forth for securing the plates together edgewise by uniting devices disposed at the inner faces of the plates are

merely exemplifying, but they have our preference over other known devices for the purpose.

The structure thus far set forth may constitute a safe with a single thickness of wall and it will, of course, be understood that one side of the safe will be provided with a suitable doorway and door and door accessories.

Our present invention comprehends the disposition, within the complete safe-wall thus far referred to, of a second safe-wall of similar construction, or a second safe, to express it otherwise, not dependent on the first safe for its integrity, and within this second safe there may be constructed a third similar safe, and so on for any desired number of wall layers, and in this system of construction the only feature necessarily common to all of the safes will be such features as pertain to the door-opening at the door and the door accessories.

Proceeding with the drawings: 12, indicates a second safe-wall disposed within the previously described safe-wall and similarly composed of plates joined edge to edge, whereby there would be produced a safe with two walls substantially independent of each other, the uniting devices for the edges of the plates of the outer safe being disposed in the space between the inner safe and the outer safe. 13, a third safe, constructed substantially like the first and second safe and disposed within the second safe: and 14, a fourth safe of the construction before described and disposed within the third safe, the joints of all the safes breaking joint with each other.

The construction thus far described provides for a safe having four wall thicknesses which are not dependent upon each other except in the matter of mere support and of such door-opening features as may be common to all of the safes. The number of safes which may thus be disposed one within the other is not limited, and while Figs. 3 and 4 illustrate a compound safe of two safe-elements, and while Fig. 2 illustrates a safe of four safe-elements, our invention comprehends any desirable plurality of safe-elements.

In Figs. 2, 3 and 4 the several safe-elements are quite independent of each other, in the sense that the fastening means at the plate-joints of one of the safes does not perform as fastening means for the plate-joints of the contiguous safe. But this independence of the fastening means of one safe from the plates of the other safe is not essential. For instance, in Fig. 5, we illustrate the wall-work of two safes on the general principle heretofore set forth but in which the fastening devices at the joints of the outer safe are utilized as uniting devices at the joints of the plates of the inner safe.

In Fig. 5:—15, indicates two plates of the outer safe at the joint between them: 16, bars secured thereto and corresponding with bars 9 previously described: 17, a cover-plate secured to the bars 16 and corresponding with the cover-plate 10 previously described: 18, the plates of the inner safe, corresponding with the plates of safe 12 previously referred to, the joint between plates 18 being in substantially the same plane as the joint between plates 15: and 19, screws passing through perforations in plates 18 and screwing into the cover-plate and bars which unite the outer plates. In the illustration in Fig. 5 these screws are shown as screwing into both the cover-plate and the bars, and these parts, being of machinable metal, readily permit of this construction. If the plates 18 of the inner safe are of unmachinable metal then the holes of the screws 19 will require to be cast in the plates.

The construction of compound safes in accordance with our present invention well lends itself to economical and otherwise advantageous shop procedures, owing to the fact that, given a compound safe of three components, each of these components may be separately constructed and in any order desired, thus permitting work upon one component to be going on while work upon another component is going on independently or before the other component is started. Later, either as a shop process or in ultimate erection at the place of use, the safe components, having been disassembled for shipment, may be erected in proper order, beginning with the outside component.

The construction of our compound safe or vault is carried forward as follows. The plates forming the sides and corners of the outer component of the safe are formed of unmachinable manganese steel. The plates are assembled edge to edge with the joints between them formed by means disposed exclusively upon the inner surface of the wall, and the result is a safe of undrillable and uncuttable walls, the walls being incapable of separation from each other by operations upon the exterior of the safe. Such a safe is of itself not new but its wall is of limited thickness owing to the fact that manganese steel castings require to be heat treated in order to render them useful for safe purposes, and in the case of very thick plates of manganese steel the heat treatment will penetrate for a limited distance only leaving the central portion of the plate in unfit condition. Now, having the complete single thickness safe thus far referred to, and desiring greater aggregate thickness of walls, we proceed to build a similar complete safe, but of smaller size, within the first safe, this inner safe being formed in a similar

manner of unmachinable plates joined at their edges by securing devices disposed on their inner faces, the fastening devices employed in uniting the plates of the outer safe 5 occupying the space between the outer surface of the inner safe and the inner surface of the outer safe. That portion of the space not occupied by the fastening devices being left empty or being filled with non-conducting material, as desired. In the two-component safe, as thus constructed, neither component is dependent upon the other component for its stability, and the union at the edges of the plates of the components 10 is effected by means and operations entirely within the safe. If it should prove possible to attack and destroy the outer component the inner component, of equal security, would still remain. Wanting a still greater 15 thickness of wall we construct a third safe within the other two, in the same manner, and we can carry this multiplication of safes as far as deemed desirable, and if it were possible to destroy the outer safe the next 20 inner one presents equal resistance to attack, and so on throughout the series of safes. An outer component cannot be removed from an inner component, and the process of construction proceeds from the 25 outside inward.

While the ultimate erection of the safe must proceed from the outside inward it is not essential that that method shall be followed in the original shop construction as 30 inner components may be proceeded with and completed without waiting for the completion of outer components, but later, the several safes must be dismantled for ultimate permanent erection, and in this permanent erection the procedure must be from 35 the outside inward.

It has been proposed to construct a compound safe whose outer component could be readily dismantled by outside operations, 40 this dismantling giving access to an innermost component, the object being to provide for the quick carrying away of the inner component in unopened condition in case there was not time to open the several doors 45 and remove the contents of the inner component. This system of safe construction will at once be recognized as being directly opposed to the system on which our invention is founded, for in our system in case 50 any dismantling is, under any circumstances called for, that dismantling must proceed from the inside, the inside component being first dismantled and removed, and so on with each succeeding outer component. Our 55 construction is not to be viewed as at all analogous to a compound receptacle having its outer member readily removable from its inner member, as in the example above referred to, or as analogous to a construc-

tion in which the outer member may be 65 opened and an inner member removed therefrom bodily, as in the case of the tin box withdrawable from a safety deposit box.

We have explained that when the outer component is done there is produced a complete safe which can be dismantled only by inside operations, and that inner safes may be built within the outer safes.

It should be here stated that if one of our compound safes or vaults be constructed 75 and it be later thought that additional thickness of walls is desired, other safes or safe components may be erected within those already existing.

In the construction of vaults whose walls 80 are formed of manganese steel castings, the peculiar resisting power of the metal, owing to its non-cutability, is mainly depended upon and a comparatively thin wall becomes available, indeed, owing to the fact that the 85 manganese steel castings take on their peculiar tough and non-cuttable character only after being heat treated, and owing to the fact that the heat treatment does not become effective when the metal is thick, the 90 comparative thinness of the walls becomes specially desirable. But in many cases of modern vault-construction the vaults form good-sized rooms, and in the construction of such vaults with thin walls it is found 95 that the thin walls, no matter what their merit regarding impenetrability may be, are lacking in stability, in some cases so deficient in this respect as to permit of collapse. In our improved construction we 100 may construct the outer safe, complete in itself, and temporarily braced in such manner as to secure stability, the next inner safe being then constructed, the fastening devices between the plate-edges of the outer safe lie 105 in the space between the outer safe and the next inner safe and in contact with the outer surface of the next inner safe. When this has been done, the two safes reinforce each other by reason of the fastening devices in 110 the space between them, and the ribs involved in the fastening devices form in themselves stiffening devices in addition to acting as struts between the inner and outer safes, and so on with the succeeding inner 115 safes. When the composite structure is completed there is therefore formed, not only a succession of safes each in itself of practically impenetrable character, but each reinforcing the other whereby there results 120 a compound thick wall with impenetrable components and of great stability.

We claim:

Safe or vault construction comprising, 125 edgewise abutting outer wall plates of unmachinable metal, uniting devices disposed on the inner side of said plates at the joints between them, edgewise abutting inner wall

plates disposed within the outer plates and in contact with the uniting devices of the outer plates, and uniting devices disposed on the inner surfaces of the inner plates at the joints between them and adapted to have their inner surfaces in contact with additional edgewise abutting wall plates having their inner edges provided with uniting devices, the joints between the edges of the

outer wall plates breaking joint with the joints between the edges of the inner wall plates, combined substantially as set forth.

MOSES MOSLER.
CARL BARTELS.
